ADJUSTABLE-BULKHEAD-CARGO-PRESS
STRUCTURE FOR RAILWAY CARS

Hugh Vernon Wynn, Hayward, Calif.

Application November 7, 1934, Serial No. 751,821

3 Claims. (Cl. 105—369)

This invention relates to improvements in railway refrigerator cars and pertains particularly to an improved bulkhead structure which combines adjustable features with an efficient and practical cargo press.

The primary object of the present invention is to provide a practical adjustable bulkhead and cargo press, which will greatly facilitate loading of freight, especially fresh fruits and 10 vegetables, and provide safer and more economical transportation for that class of freight.

Another object of the invention is to provide a bulkhead structure of strong, practical, convenient and durable design, which may be easily 15 and quickly shifted to the desired position after the necessary computation has been made as to the amount of space the cargo will take, and which, after cargo has been stowed, may be tightened and secured from outside of car to insure 20 a tight load.

A further object of the invention is to provide a shiftable bulkhead-press structure which will insure a tight load and reduce to a minimum the shifting and breaking of packages and the 25 consequent spoilage of goods; which shifting and breaking of packages at present occurs frequently as a result of the collapse or improper construction of temporary bulkhead pads or center bracing structures.

Still another object of the invention is to provide an adjustable bulkhead-cargo press structure in which the initial expense of installation constitutes the entire expense involved in its use, thereby eliminating the present expense and 30 waste of lumber involved each time a car is loaded when temporary padding or center-bracing structures must be built to take up extra space, and then torn out when cargo is removed and it is necessary to clean the car for a new 35 and usually different load.

Other objects of the invention reside in the novel means by which the movable bulkhead is mounted for movement; the novel means by which the shifting of the bulkhead is effected; 40 the novel means by which the cargo may be pressed to tighten load; the novel means by which the pressing means may be locked after load has been tightened sufficiently to insure safe transit; the novel means by which certain 45 parts of the structures are housed so that they may be constantly kept bathed in grease or other suitable lubricants; and the novel placement of aforesaid parts and their housings adjacent side walls of car in ice bunker so that said parts and 50 their housings will not interfere in any way with

storage of ice or installation of temperature control apparatus.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a vertical longitudinal sectional view through one end of a refrigerator car showing the structure embodying the present invention in position therein, the section being taken substantially upon the line 1—1 of Fig. 3.

Fig. 2 is a sectional view taken substantially upon the line 2—2 of Fig. 1;

Fig. 3 is a sectional view taken substantially upon the line 3—3 of Fig. 1;

Fig. 4 is a cross-sectional view taken substantially upon the line 4—4 of Fig. 3;

Fig. 5 is a vertical sectional view taken substantially of the king sprocket supporting bracket, the section being on a plane parallel with the ice screen;

Fig. 6 is a detail sectional view taken substantially upon the line 6—6 of Fig. 1;

Fig. 7 is a detail view taken substantially of the press lever and its securing means.

Referring now more particularly to the drawings wherein like numerals of reference indicate corresponding parts throughout the several views, there is shown diagrammatically in Fig. 1 one end in vertical section of a car wherein the roof is indicated by the numeral 1, the end wall is indicated by the numeral 2, and the floor is indicated by the numeral 3.

The structure embodying the present invention comprises two main units, one of which is indicated generally by the numeral 4 while the other is indicated generally by the numeral 5.

The unit 4 is fixed and constitutes the ice bunker bulkhead which is spaced from the end wall 2 of the car and is secured between the top, bottom and side walls in the manner shown to form the ice bunker 6. This screen bulkhead is made up of the top angle beam 7, the vertical side angle beams 8 and the vertical I beams and perforated plates 9 and 10 respectively. The vertical I beams are formed by the flanges of the perforated plates being bolted firmly together in the

manner shown in Figure 4 to form a strong screen-like wall structure being secured at top and bottom in the manner illustrated.

Secured between the structure 9—10 and end 5 wall 2 of the car are the ice grates 11 upon which the ice is supported when placed in the bunker.

Each of the vertical side angle beams 8 of the ice screen has the two openings 12 formed therethrough, one of which is near the top while the 10 other is near the bottom, and each of these openings is surrounded by the small bolt openings 13. Mounted upon the rear side of each of the ice screen angle bars 8 and adjacent the side wall of the car is a pair of cylinders or housings each 15 of which is indicated by the numeral 14. These 20 housings connect between the beams 8 and the adjacent side and end walls of the car and as is shown each has a plate 15 on its forward end which abuts the rear side of the angle beam and has bolt holes therein which register with the bolt holes 13 of the beam 8 to receive securing 25 bolts 16. At their other ends the housings have the ears 17 which are apertured to receive supporting screws or bolts which are driven into the end wall structure 2, and intermediate its ends each housing 14 is provided with the apertured ears, 18 and 19 by means of which the further attachment of the housing to the angle beams 8 and the adjacent side walls of the car is effected.

30 Each of the housings 14 is provided with a plugged opening 20 by means of which grease may be injected thereto for lubricating an enclosed jack screw which will be hereinafter described.

The bolts 16 which secure the plates 15 of the 35 housings 14 to their respective angle beams, also secure to the forward faces of these beams 8 the split collars 21. The inner faces of each of these collars 21 is annularly recessed or channeled to receive the collar 22 which is formed upon one 40 end of the hub portion 23 of a jackscrew sprocket 24.

Through each of the four sprockets 24, which are interiorly threaded, there extends a jackscrew 25 which passes through the angle beam 8 45 into the adjacent housing 14 and each of these screws has a head-plate 26 upon its forward end.

The central vertical channel beam 35 is provided at a point near to its upper end with an aperture 27 and rotatably mounted in this aperture is one end 28 of the hub portion of a king 50 sprocket which is indicated generally by the numeral 29.

The hub of this sprocket is provided on its forward end with a key hole opening 30 for the purpose hereinafter set forth; and on the rear end provision is made for securing the end of a shaft 36 which extends through adjacent end wall of the car. Secured to the forward face of the beam 35 against which the king sprocket 29 is positioned, is a bracket 31 which has a central offset portion 32 provided with the opening 33 in which the forward end of the sprocket 29 is rotatably mounted. The end portions 34 of the bracket 31 are suitably secured to the forward face of the 65 beam 35.

The four jackscrew sprockets 24 are connected by the operating chain 40 which as shown passes over the top of the king sprocket 29, passing through the bracket 31 which supports the king 70 sprocket in position. It will then be seen that by turning the king sprocket 29 all the jackscrew sprockets 24 will be turned through the medium of the chain 40 and the longitudinal movement of the screws 25 effected. There are two ice bunkers 75 6 in each car, one adjacent each end, the area

between these bunkers constituting the freight compartment. This area is indicated by the numeral 41.

Adjacent each bulkhead 4 each side wall of the car forwardly of the bulkhead has countersunk therein and secured thereto the two vertically spaced longitudinally extending hangar tracks each of which is indicated generally by the numeral 42. Each of these tracks consists of an elongated steel plate 43 which is pressed to have 10 formed therein the longitudinal channel 44. The side walls of the car are provided with suitable recesses to receive the channels 44 so that the plates 43 will be flush at their outer surfaces with the face of the wall.

15 Mounted in front of the ice screen bulkhead 4 is the adjustable or floating bulkhead 5. This floating bulkhead structure consists of the framework made up of the top and bottom horizontal beams 45 and 46, the vertical side beams 47 and 20 the intermediate vertical beams 48, and secured transversely of the vertical beams 47 and 48 is the pad of planks 49 which does not extend entirely to the top and bottom edges of the framework so that open areas 50 are left across the top 25 and bottom of the floating bulkhead which are covered by the spaced bars or grill work 51 through which the free movement of air is allowed for ventilating purposes.

30 The vertical side beams 47 of the floating bulkhead 5 have secured to the outer edges thereof the hangar elements 52 each of which slidably engages in the channel 44 of the adjacent hangar track 42.

The butt-plates 26 of the jackscrews 25 are 35 securedly bolted to the rear faces of the adjacent vertical channel beams 47 of the floating bulkhead.

At its upper central portion the floating bulkhead 5 is provided with a keyhole opening 53 of 40 the same design as the opening in the forward end of the hub of the king sprocket 29 for the purpose of inserting the crank 55 to effect the rotation of the king sprocket 29 and the consequent motion of the entire mechanism from the 45 inside of the car. The mechanism moves the floating bulkhead 5 in the desired direction to increase or decrease the length of the freight compartment 41.

On the adjacent end wall of the car, outside, 50 and mounted upon the end of the shaft 36 is a ratchet and lever assembly, generally indicated by the numeral 37, by means of which the movement of the bulkhead 5 may be effected from outside the car. Said lever being long enough to be 55 operated by a man on the ground, and with its upper end cast with or firmly riveted to the housing or framework of the ratchet assembly. The ratchet assembly is suitably housed and carries within its housing the ratchet pawls 57 and 58. The pawls are designed and hung in such manner that they are operable by gravity, and, as can readily be seen, should the lever be moved appreciably to either side the force of gravity would cause the pawl on that side to drop into connection with the ratchet gear. The positive pawl 58 being latchable, and shown in a latched position, by means of the small fulcrum lever 59 for holding it in continued connection with the ratchet gear to prevent any reverse movement of the 60 mechanism. The fulcrum lever is operable by means of the latch hasp 60 near the end of the ratchet lever, to which it is connected by the rod 65 extending down the lever.

66 The hasp 60 is designed to slide up and down 75

the lever to a position above or below the pin 61; the position above the pin holding the fulcrum lever 59 out of engagement with the pawl 58, and leaving the ratchet in neutral, while the position

5 below the pin, (in which hasp is shown in drawings) forces the fulcrum lever against the positive pawl 58, holding it in engagement with the ratchet gear and preventing the reverse movement of same. In the latter position the latching hasp 60 will engage a staple 62 set in the end wall of the car, through which is then thrust the eccentric bolt 63 in which position it may be sealed by an ordinary car seal thrust through the slot 64 near its lower end. By this arrangement 10 the ratchet lever is held against movement, and the pressure of the fulcrum lever 59 holds the pawl 58 in connection with the ratchet gear to prevent reverse movement of any part of the mechanism.

15 The dotted lines 59½ and 60½ show latch lever and hasp in unlatched position. The pin 61 will hold hasp up in this position while ratchet lever is being used either positive or negative, or while mechanism is being operated from inside of car.

20 In the operation of the present adjustable bulkhead-press structure the car loader after determining the approximate amount of space which will be required for the cargo which is to be placed in the freight compartment 41, and thus determining the extent to which the bulkhead 5 must be shifted to increase or decrease the length of the freight compartment, first unlatches ratchet lever 37 at the end of car on the outside, being sure that 25 dogs 57 and 58 are completely clear of the ratchet wheel.

25 He then extends through the opening 53 in the floating bulkhead structure 5, a crank of the character indicated by the numeral 55, the forward end of which is provided with a cross pin 56 which engages in the opening 39 in the front hub of the king sprocket 29. By then turning the crank in the proper direction the chain 40 will operate the jackscrew sprockets and the moveable bulkhead 5 will be caused to move in the desired direction.

30 After the bulkhead has been properly adjusted and the car loaded, the car-loader will go to the end of the car, outside; standing to one side of the coupler in a position facing the car he will raise the ratchet lever to his right, allowing the positive pawl 58 to drop into engagement with the ratchet wheel or gear, then, by pulling the lever back to the vertical position he causes the shaft 36 to turn to the right, operating the adjusting mechanism within the car and pressing the cargo; he repeats the operation as many times as necessary until the cargo is pressed to the desired tightness. (To withdraw the pressure, this operation should be reversed, lifting the lever to the left instead of the right.)

35 After the load has been sufficiently tightened, the lever 37 should be returned to the vertical position and latched as hereinbefore described. The eccentric bolt 63 is fastened by means of a regulation car seal thrust through the slot 64 in its lower end, the number of which is to be recorded on the manifest along with the numbers of seals used on ventilators and doors.

40 Having thus described the invention, what is claimed as novel is:—

45 1. In a refrigerator rail-road car having ends and longitudinal boundaries, and, adjacent an end wall, a space or bunker for the storage of ice or temperature control apparatus, said ice

5 bunker being separated from the freight compartment by a fixed bulkhead; an adjustable bulkhead-cargo-press structure; a slideable bulkhead within the freight compartment, adjacent and paralleling the fixed bulkhead; a jack-screw 10 and screw sprocket and chain assembly disposed between said bulkheads for effecting the movement of the movable bulkhead longitudinally of the car relative to the fixed bulkhead; means for securing the said screw sprockets to the fixed bulkhead; an idle king-sprocket engaging said screw sprockets by means of said chain for co-ordinative control of the entire sprocket assembly; a means for operating the king-sprocket 15 from within the car; a plurality of housings carried by the longitudinal boundaries of the car within the ice bunker for the protection and lubrication of the jack-screws which extend thereinto; a latchable, gravity action ratchet 20 and lever assembly mounted upon the end wall of car outside, and connected to the king-sprocket by a shaft or other means, for effecting the movement of the assembled mechanism from outside the car.

25 2. In a railroad car of the described class; an adjustable bulkhead-cargo-press structure; a slideably mounted movable bulkhead within the freight compartment, adjacent and paralleling the fixed ice bunker bulkhead; a plurality of jack-screw elements adjacent the longitudinal boundaries of the car and connecting said bulkheads; a plurality of internally threaded nut-like elements, each outwardly formed to provide a sprocket wheel, and each having threadably 30 engaged therein one of the jack-screws which extend through the fixed bulkhead into the ice bunker; means by which the said nut-like elements may be rotatably mounted upon the fixed bulkhead; an idle king-sprocket mounted 35 parallel with the fixed bulkhead and engaging the said nut-like elements by means of a sprocket chain for effecting the co-ordinative rotation of same; a means for operating the king-sprocket from within the car; a plurality of longitudinal housings within the ice bunker and carried by the longitudinal boundaries of the car, each being provided with a plug or other connection for the injection of grease and each having movably housed therein the extended portion 40 of one of the aforesaid jackscrews; a gravity operated ratchet assembly mounted outside upon the end wall of the car and carried by a shaft extending from the king-sprocket, and having a lever extending therefrom; a small fulcrum lever for control of the positive pawl in 45 said ratchet; means for operating the fulcrum lever from the end of the lever which extends from the ratchet; a means for latching the total assembly against unwanted movement.

50 3. In a railroad car of the described class; within an ice bunker, a plurality of housings disposed adjacent the longitudinal boundaries of the car, each with an open end in alignment with a hole in the ice bunker bulkhead; a plurality of internally threaded nut-like elements 55 outside the ice bunker upon the fixed bulkhead, each being rotatably mounted in alignment with one of said housings, and each having its outer surface formed to provide a sprocket wheel; means for rotatably mounting said nut-like elements; a king-sprocket mounted upon the fixed bulkhead; a means for connecting said sprockets to effect their simultaneous rotation; a slideable bulkhead disposed within the freight compartment 60

65

70

75

ment adjacent and parallel with the fixed bulkhead; means for slidably supporting said movable bulkhead; a plurality of jackscrews disposed longitudinally of the car, each having an end threadably engaging one of the aforesaid nut-like elements and each at its other end being secured to the movable bulkhead at a point ad-

jacent the longitudinal boundaries of the car; a means for effecting the movement of the entire assembly from within the car; a gravity ratchet and lever assembly mounted outside the car for operating the mechanism from without the car. 5

HUGH VERNON WYNN.
